CLAIM

(57) The ornamental design for a popsicle mold, as shown and described.

DESCRIPTION

FIG. 1 is a perspective view of a popsicle mold showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof; and,

FIG. 9 is another exploded perspective view thereof.

1 Claim, 9 Drawing Sheets
